UNITED STATES PATENT OFFICE.

JAMES E. SHAVER, JR., OF PHILADELPHIA, PENNSYLVANIA, ASSIGNOR TO UNDERWOOD TYPEWRITER COMPANY, OF NEW YORK, N. Y., A CORPORATION OF DELAWARE.

STENCILING MACHINE.

Application filed May 26, 1923. Serial No. 641,533.

To all whom it may concern:

Be it known that I, JAMES E. SHAVER, Jr., a citizen of the United States, residing in Philadelphia, in the county of Philadelphia and State of Pennsylvania, have invented certain new and useful Improvements in Stenciling Machines, of which the following is a specification.

This invention relates to duplicating-machines in which a perforated hollow cylinder or drum is covered with an ink-blanket and a stencil-sheet is laid upon the blanket, the paper to be stenciled being run between the stencil-sheet and pressure roll, the ink being applied to the interior of the cylinder 10 and taken up by the ink-blanket upon the exterior thereof.

Among the objects of the invention are to provide an improved stop-mechanism for temporarily arresting the cylinder at the end 20 of each complete revolution; to provide means movable on the cylinder to indicate the depth of the top margin on the printed sheet, to provide the frame with permanently-attached supply and delivery tables, which may be folded in a small space when not in use, to provide means on the supply 25 table for accurately gaging the side edges of the work-sheet pile, to provide means to prevent the ink applied to the interior of the cylinder from working out over the edges thereof, and to provide an improved construction for the roller-bearings on which the end of the cylinder rotates.

According to one feature of the invention, the cylinder may be provided with a pair of lugs adjustable along the rim thereof, which co-operate with a bell-crank lever mounted on the frame of the machine, to cause the movement of the cylinder to be stopped at the end of each revolution, and to check the recoil thereof, so that the sheets to be printed may be started through the machine in proper relation to the stencil-sheet.

Another feature of the device resides in providing the handle upon which the stops are mounted with a scale, movable along the cylinder when the handle and stops are adjusted, to indicate, at a glance, the depth of

the top margin which will be formed on the 50 printed sheet.

Heretofore, in machines of this kind, the supply and delivery tables have been detachably mounted on the frame of the machine, and, in some cases, became lost or misplaced 55 when detached from the frame of the machine. It is a feature of this invention that the supply and delivery tables are permanently attached to the frame of the machine, and pivoted in such a way that they may be 60 folded upwardly, toward the stencil-cylinder, so as to fit within the cover of the machine. The supply table has pivoted to the underneath side thereof a pair of brackets which support the table against the frame 65 when in effective position, and, when the supply table is swung upwardly, toward the cylinder, these brackets swing inwardly on their pivots and fit closely against the bottom of the supply table.

Another feature of the invention resides in the provision of an improved side-edge gage for accurately gaging the edges of the work-sheet. One important feature of this gage resides in the abrupt right-angular corner which replaces the rounded corner in existing gages, and prevents the side edges of the work-sheets from riding up the side of the gage.

Another feature of the invention is the provision of ribs upon the interior of the cylinder which prevent the ink applied thereto from spreading to the outer edge of the cylinder. The corners between these ribs and the cylinder-walls may be rounded to 85 prevent the accumulation of ink therein.

According to another feature of the invention, the ball-bearing rollers upon which one end of the cylinder revolves may be constructed so that the rim, hub and balls are 90 held in unitary assembly by a retaining flange carried by the rim.

Other features and advantages will hereinafter appear.

In the accompanying drawings, 95
Figure 1 is a side elevation of the machine with certain parts shown in section.

Figure 2 is a perspective view of the ad-

justable handle and scale, showing a section of the cylinder upon which they are mounted in the assembled machine.

Figure 3 is a sectional view of the handle and scale mounted on the cylinder.

Figure 4 is a longitudinal cross-section.

Figure 5 is a side elevation, showing the position of the supply and delivery tables when the cover is on the machine.

Figure 6 is a plan view of the supply table and side-edge gage.

Figure 7 is a section of the supply table, showing the pivoted supporting brackets.

Figure 8 is a bottom plan view of the brackets swung inwardly against the supply table.

Figures 9, 10 and 11 show the stop-mechanism at different positions in its operation.

Figure 12 is a cross-section of the roller 20 for supporting the cylinder.

In the embodiment illustrated, the base 1 is provided with end frames 2 and 3, one of which carries a trunnion 4 upon which one end of the stencil-cylinder 5 revolves, the

other end of the cylinder being supported in the yoke-shaped frame 2 and revolving on trundles 6, 7 and 8 held in this frame.

The cylinder 5 is provided with an adjustable handle 9 locked to the cylinder-rim 10 by set-screws 11 and projections 12 and 13 which slidably ride in grooves 14 on the cylinder.

A fiber pad 10^a, inserted between the handle 9 and the rim 10, holds the handle firmly when the set-screws are set and reduces the strain upon lugs 12 and 13.

Upon the handle-bracket are mounted two lugs 15 and 16 which co-operate with a bell-crank lever 17 pivoted upon the frame to cause the movement of the cylinder to be arrested at the end of each complete revolution for the introduction of a work-sheet.

In operation, the forward lug 15 slides over the arm 18 of the bell-crank lever and forces this arm downwardly, which elevates the arm 19 of the bell-crank lever and throws it into the path of the lug 16, so as to stop the motion of the cylinder.

The operator then imparts a slight reverse movement to the cylinder, whereupon the spring 20 draws the bell-crank downwardly against the stop 21 to release the rear lug 16 for further forward rotation, and at the same time the arm 18 of the bell-crank lever is elevated, so as to contact with the rear of the front lug 15 and limit the reverse movement of the cylinder.

This is the position of parts illustrated in Figure 9. In order to release the stencil-sheet from the cylinder, it may be desirable, at this stage of the operation, to move the handle further in a reverse direction, that is, to the left as viewed in Figure 9. To accomplish this, the operator lifts the finger-piece 19^a on the bell-crank and withdraws the arm 18 from the path of the lug 15, thus freeing the cylinder for reverse

movement. The position of the handle and lugs, therefore, determines the position of the cylinder when the work-sheet is introduced, and hence determines the depth of the margin which will be formed at the top of the 70 printed sheet.

The depth of this margin is equal to the space between the handle and the top of the stencil-sheet, and means are provided for readily measuring this space consisting of 75 a graduated scale 22 attached to the handle 9 and adjustable therewith around the cylinder, the scale indicating to the operator, at a glance, the distance in inches, or other convenient measuring units, which the handle 80 is spaced from the top of the stencil-sheet. One end of the scale is attached to the handle by means of lugs 23, and the opposite end of the scale is held upon the cylinder by the bracket 24 attached to segment 25 which is fixed to the handle and moves around the cylinder-rim 10 therewith. The cylinder may be provided with a groove 26 for the scale 22 to slide in.

The supply table 27, which is provided with an extensible top 28, is pivoted to the frame at 29, and is adapted to swing upwardly against the cylinder, as illustrated in Figure 5. The top 28 slides on guides 29^a which are secured to flanges 30^a on the supply table 27. A pair of brackets 30 are pivoted at 31 to the guides 29^a, and, in its working position, the edges 32 of the brackets rest against the frame of the duplicator, to rigidly support the supply table. When the supply table is folded upwardly against the cylinder, these brackets swing inwardly upon their pivots and fit closely against the underneath side of the supply table, as illustrated in Figure 8. The delivery table 33, also provided with an extensible top 34, is pivoted to the frame in a similar manner at 35, and can also be swung upwardly toward the stencil-cylinder, so as to fit within the cover of the machine. This arrangement secures the delivery table and the supply table permanently to the frame of the machine, so that there is no danger of them becoming misplaced, as often happens with the detachably connected supply and delivery tables of the prior machines.

Mounted on the top of the supply table is a side-edge gage which consists of an angle-bar 36, to the rear of which are attached two parallel brackets 37 provided with saw-toothed slots 38 therein. A pair of set-screws 39 co-operate with the saw-teeth in the slots in the brackets to secure the gage firmly on the table in any of its adjusted positions, and since the saw teeth are in registry the two brackets secure parallel adjustment of the side edges of the gage. In adjusting the gage registering teeth are brought into engagement with the set-screws 39 and as the edge of the gage is 125 130

parallel to the registering teeth; it is also parallel to the sides of the table 27 and to the direction in which the copy-sheets are fed to the cylinder. The sharp corner in 5 the angle of the gage, replacing the rounded corners in the present gages, prevents the side edges of the work-sheet from riding up the side of the gage and working out of alignment.

10 The interior of the cylinder is provided with inwardly-extending ribs 40 at the margin of its printing surface, which prevent the ink applied to the interior of the cylinder from working out over the ends 15 thereof. The corners between the ribs and the cylinders are rounded at 41, so as to facilitate cleaning of the machine and prevent the accumulation of ink at these points.

10 A detail sectional view of my improved 20 ball-bearing roller, appearing in Figure 4, for supporting the outer rim of the cylinder for rotation is shown in Figure 12. According to the embodiment shown, a fixed member 41^a is mounted on a stud 43 attached to the frame 2 of the machine, and provides a ball-race 44 for the balls 45 of 25 the trundle or roller 7. The rim of the roller is provided with an integral flange 46 extending inwardly over a flange 49 of the fixed member, and the opposite side of the rim is turned inwardly at 47 to hold a retaining ring 48 which revolves with the rim and holds the balls and fixed member assembled in the rim, thus providing a unitary 30 bearing. The trundles or rollers 6 and 8 35 may also be of the above-described character if desired. By this construction the rim of the roller is widened so as to provide a broader bearing-surface for the cylinder, and the mounting of the rollers on the frame is simplified.

40 A soft rubber roll 50 is pressed upwardly 45 against the stencil-cylinder by arms 51 acting under the influence of cam 52 fixed on the movable shaft 53, the pressure being adjustable to secure proper contact between the stencil-sheet and the paper. A brake 54, pulled downwardly by spring 55, is provided to hold the cylinder from rotation 50 when the machine is not in use; the cam 56 on shaft 53 acting to release the brake when the roll 50 is elevated.

55 Variations may be resorted to within the scope of the invention, and portions of the improvements may be used without others.

Having thus described my invention, I claim:

1. In a duplicating machine, the combination 60 with a revoluble cylinder, of an escape- 65 ment mechanism comprising a pair of lugs mounted on the cylinder, means actuated by one lug to place an obstruction in the path of the other lug to arrest the movement of the cylinder, means to adjust the lugs around 65 the cylinder to determine the point to be

stopped; and a scale adjustable around the cylinder with the lugs to indicate the distance between the stopping point and the top of the stencil-sheet.

2. In a duplicating machine, the combination 70 with a revoluble cylinder, of an escape- 75 ment mechanism comprising a pair of lugs mounted on the cylinder, means actuated by one lug to place an obstruction in the path of the other lug to arrest the movement of the cylinder, means to adjust the lugs around the cylinder to determine the point to be stopped, and a scale adjustable around the cylinder with the lugs to indicate the depth 80 of top margin which will be formed on the printed sheet.

3. In a duplicating machine, the combination 85 with a revoluble cylinder, of a handle adjustable around the rim thereof, a pair of lugs mounted on the handle, means actuated by one lug to project an obstruction into the path of the other lug to arrest the movement of the cylinder, and a scale attached to the handle and adjustable around the cylinder to indicate the depth of top 90 margin which will be formed on the printed sheet.

4. In a duplicating machine, a revoluble 95 cylinder, means to stop the cylinder at the end of each complete revolution in position 100 for a work-sheet to be fed into the machine, adjustable means to vary the stopping point with relation to the top of the stencil-sheet, and a scale movable with the adjustable means to indicate the amount of adjustment.

5. In a duplicating machine, a revoluble 105 cylinder, a stencil-sheet thereon means to arrest the movement of the cylinder in position for a work-sheet to be fed into the machine, the distance between the stopping point and the top of the stencil-sheet determining the depth of top margin on the printed sheet, adjustable means to vary the stopping point around the cylinder to change 110 said top margin, and a scale on the cylinder movable with the adjustable means to indicate the depth of top margin which will be formed on the work-sheet.

6. In a duplicating machine, a revoluble 115 cylinder, a stencil-sheet thereon, a handle adjustable around the cylinder, and a scale movable with the handle to indicate the distance from the handle to the top of the stencil-sheet.

7. In a duplicating machine, a revoluble 120 cylinder, a stencil-sheet thereon, a handle adjustable around the cylinder, and an arcuate scale attached to the handle and slidale 125 around the cylinder to indicate the distance from the handle to the top of the stencil-sheet.

8. In a duplicating machine, a revoluble 130 cylinder, a stencil-sheet thereon, a handle adjustable around the cylinder, and an arcuate scale attached to the handle and slidale

around the cylinder to indicate the distance from the handle to the top of the stencil-sheet, said cylinder having a groove therein to receive said scale.

5 9. In a duplicating machine, the combination of a revoluble cylinder, a handle adjustable around the rim thereof, lugs to hold the handle on the rim, means to lock the handle in adjusted position, and a compressible pad 10 between the locking means and the cylinder rim to reduce the strain on the holding lugs.

10 10. In a duplicating machine, the combination of a frame, a work-cylinder revolvably mounted thereon, and a supply table for 15 feeding work to said cylinder, including a main section pivoted to said frame, longitudinal flanges on said main section, a pair of longitudinal guides extending parallel to the face of said main section, an auxiliary 20 section mounted to slide in said guides and movable from an extended horizontal position wherein it adds to the area of said main table to a collapsed position alongside said main section, and swingable upwardly with 25 the main section about its pivot point to an upright position alongside said cylinder and within a cover for said machine, and brackets pivoted to said guides, engageable with 30 said frame and foldable inwardly to a position adjacent said table.

11. In a duplicating machine having a work-cylinder, the combination with a main frame, of foldable and compactible work-feeding and work-receiving tables pivoted to 35 the sides of said frame, in positions to fold up upon opposite sides of said cylinder, each of said tables including both a main portion and a portion which is retractable relatively thereto, each main portion swingable up, together with its said retractable portion, into an upper or collapsed position alongside the cylinder, to bring the free end of the main portion adjacent the level of the top of the cylinder, each retractable portion 40 being movable to a position substantially within the contour of its main portion in its folded-up position, to compact the tables within a cover of a size substantially fitting over the cylinder and frame.

50 12. In a duplicating machine, the combination of a revoluble stencil-cylinder, a frame having upwardly-extending portions for supporting said cylinder for rotation, one of said portions being of yoke-shape, 55 and supply and delivery tables, on opposite sides of said cylinder, extending inwardly between the upwardly-extending frame-portions and pivoted thereto for movement upwardly to positions alongside said cylinder 60 and within a cover for said machine.

13. The combination with a duplicator, of an extensible supply table pivoted to the frame thereof, and brackets pivoted to the underneath side of the supply table to provide a substantial support for said table

when extended in horizontal position, said brackets arranged to fold inwardly against the underneath side of the supply table, the latter being swingable upwardly from its horizontal position and collapsible to fit 70 within the cover of the machine.

14. The combination with a duplicating machine, of an extensible supply table pivoted to the frame thereof, and triangular brackets pivoted to the underneath side of the supply table to provide a substantial support for said table against the frame of the duplicator when said table is extended in horizontal position, said brackets arranged to fold inwardly against the underneath side 80 of the supply table, the latter being swingable upwardly from horizontal position and collapsible so as to fit within the cover of the machine when not in use.

15. The combination with the supply table of a duplicating machine, of an adjustable side-edge gage for work-sheets, said gage including a sheet-guiding member, a pair of brackets provided with saw-toothed 90 slots at the rear of said member, and a pair of set-screws in the slots and engaging the saw-toothed edges to hold said member in position on the table, the teeth of said slots being arranged in pairs on lines parallel to the sheet-guiding member to dispose the 95 guiding member parallel with the direction in which the work-sheets are fed into the machine.

16. In a duplicating machine, the combination of a frame, a stencil-cylinder revolvably supported thereon, a fixed table on said frame, a supply table pivoted on said frame and movable from a position level with said fixed table wherein it co-operates with said fixed table to feed copy-sheets to said cylinder, to an elevated position alongside said cylinder, and a side gage for said copy-sheets, extending over said fixed table and said supply table when the latter is level 105 with the former and detachably secured to 110 the latter.

17. In a duplicating machine, the combination of a perforated ink-carrying stencil-cylinder, and annular ribs on the interior of 115 said cylinder to prevent the ink working out over the edges thereof.

18. In a duplicating machine, the combination of a revolving cylinder, and annular ribs on the interior of the cylinder to prevent the ink working out over the edges 120 thereof, the corners formed by the ribs and the cylinder being rounded to prevent the accumulation of ink therein.

19. In a duplicating machine, the combination of a revolving stencil-cylinder, and annular ribs on the interior thereof for both strengthening the cylinder and preventing ink applied to the interior thereof from working out over the edges.

20. In a duplicating machine, the combi-

nation of a frame, a stencil-cylinder within the frame, and ball-bearing rollers upon which the cylinder revolves, each roller including a fixed member having a ball-race 5 and a rim revolving therearound, the rim of each roller being of greater width than the fixed member ~~thereof~~.

21. In a duplicating machine, the combination of a frame, a stencil-cylinder within the frame, ball-bearing rollers upon which the cylinder revolves, each roller including a fixed member having a ball-race, a stud 10 projecting from the frame to support each fixed member, an annular flange extending 15 inwardly beyond the edge of said fixed mem-

ber, balls mounted in the ball-race, a rim revolving upon said balls, said rim being of greater width than said fixed member, and a retaining ring for the balls carried by and revolving with the rim. 20

22. In a duplicating machine, the combination of a revolving stencil-cylinder, and annular ribs on the interior thereof bordering the printing-field for preventing ink applied to the interior thereof from working out over the edges, one of said ribs having inwardly-extending arms rigid with each other for supporting said cylinder. 25

JAMES E. SHAVER, JR.
